UNITED STATES PATENT OFFICE.

FRANK D. SHEPHERD, OF SALT LAKE CITY, UTAH.

INTERNAL-COMBUSTION ENGINE.

1,317,599.

Specification of Letters Patent. Patented Sept. 30, 1919.

Application filed February 7, 1918. Serial No. 215,866.

To all whom it may concern:

Be it known that I, FRANK D. SHEPHERD, of Salt Lake City, in the county of Salt Lake and in the State of Utah, have invented a certain new and useful Improvement in Internal-Combustion Engines, and do hereby declare that the following is a full, clear, and exact description thereof.

My invention relates to internal combustion engines of the class where the cylinder head is integral with the cylinder whether the L-head or the T-head type, and generally stated my object is to enable the spark plug to be located for center fire by a simple and readily accessible arrangement, and one which will not only not impair the efficiency of the cooling system, but will indeed promote the efficiency thereof, and my invention therefore consists in the construction substantially as hereinafter specified and claimed.

In the accompanying drawings;

Figure 1 is a top plan view of a portion of a multiple cylinder water-cooled gas engine embodying my invention, with parts broken away;

Fig. 2 is a similar view illustrating a different construction;

Fig. 3 is a vertical section on the line 3—3 of Fig. 1;

Fig. 4 is a similar section on the line 4—4 of Fig. 2;

Fig. 5 is a detail side view of the cover plate;

Fig. 6 is a view similar to Fig. 3 illustrating my invention applied to an air-cooled engine;

Fig. 7 is a similar view showing a different form of my invention applied to an air cooled engine;

In Figs. 1 to 4 I illustrate my invention as applied to an L-head four cylinder type, the cylinders being cast *en bloc* but it is to be understood that I do not limit myself to such particular construction, and cylinder 10 and head 11 are integral and provided with hollow walls to provide the water space 12. Opening laterally from the top of the cylinder is a port 13 which is under control of a puppet valve, such for example, as one of those of my patent No. 1240378 issued Sept. 18, 1917, and No. 1252501 issued January 8, 1918, but I do not limit my present invention to any particular type or construction of puppet valve. In the outer wall of the water jacket of the cylinder head is a

hole or opening 14 through which projects from the inner wall a goose-neck 16, the hole 14 and the goose-neck 16 being at the center of the cylinder, and the hole being substantially larger in size than the neck. Fitting over the hole 14 and covering or closing the same on the outside is a cover plate 17 which also passes over the outer end of the goose-neck 16 so that the latter projects above or outside of said cover plate and upon its projecting portion which is threaded is screwed a nut 18 which bears against the outer side of the cover plate and thereby serves to tightly clamp the latter against the outer wall of the cylinder head. Between the cover plate and the adjacent raised surface 110 of the cylinder head is interposed a gasket 19; and between the clamping nut 18 and the cover plate is interposed a gasket 20 and preferably the latter engages a raised surface or bed 21 which besides forming a good bearing for the gasket also thickens the cover plate and strengthens the same. Intermediate the holes for the passage of the goose-neck 16, the cover plate may be provided with any number of threaded holes 22 for connecting the water jacket with the radiator or source of supply of cooling water, and preferably around each of said openings is a raised rim or base 23 which is provided for the same reason that the similar construction is provided around the holes in the cover plate through which the goose-neck passes. At mid-length the cover plate 24 may have a rectangular raised base or tablet for fastening by screws or otherwise a name or patent plate 24.

The goose-necks 16 are open throughout their length and from their inner ends outward are internally threaded to receive the threaded portion of spark plugs 25, and beyond the threaded portion the goose-neck is enlarged in diameter so as to provide a clear space around the spark plug.

The goose-neck may have the integral one part construction best illustrated in Fig. 3 or it may have the two part construction best illustrated in Fig. 4 where it is removable, that is to say, the spark plug engaging thread may as shown in Fig. 4 be provided in a thimble 26 which is screwed into an internally threaded boss or nipple 27 projecting outward from the inner wall or shell of the cylinder head, but not reaching through the opening in the cover plate, and the outer end of the nipple 27 is engaged by

a flange or enlargement 28 on the outer end of the thimble 26 which passes through the cover hole and outside the latter is engaged by the clamping nut 18 which is screwed 5 upon the projecting portion 28 of said thimble. The opening in the outer end of the thimble 26 is given a polygonal or flattened periphery for the application of a wrench or turning tool to apply or remove the thimble from the nipple. A gasket 270 is interposed between the nipple 27 and the enlargement 28.

It will be seen that by the construction illustrated in Figs 1 to 4 I provide a center fire construction in a water cooled engine with a plurality of cylinders and at the same time provide for the ready and efficient closing by the cover plate of the opening in the outer wall or shell of the water jacket.

20 In Figs. 6 and 7 I show my invention applied to an air cooled engine, the goose-neck or threaded extension from the cylinder head as well as the cylinder head being provided with external radiating fins or 25 ribs 29, the construction shown in Fig. 6 for the attachment of the spark plug being an integral one corresponding to that of Fig. 3 while the construction shown in Fig. 7 is a removable one corresponding with that 30 shown in Fig. 4.

An important advantage from the removable thimble construction shown in Figs. 3 and 7 is that when the goose-neck or thimble is removed it provides a large opening into 35 the gas chamber of the cylinder so that the latter is more accessible for cleaning, burning out carbon, etc.

The threaded hole in the goose-neck or thimble for receiving the spark plug may be 40 cylindrical or tapering according to the style of spark plug that is used. I, of course, do not limit myself to any such detail as that because with the particular form of 45 construction of spark plug my invention is not concerned.

It will be seen that by my invention the advantageous center fire construction is simply and efficiently provided. The center fire construction is important and desirable because 50 the gas is ignited from the center and therefore burns equally in all directions putting an even pressure upon the piston head so that the force is applied directly thereto and to the crank producing more power and 55 greater speed and saving unequal wear of the cylinder walls which results from eccentric firing by reason of the side blow or pressure to which the piston is subjected.

My invention is applicable to single cylinder, as well as multiple cylinder engines.

Having thus described my invention what I claim is:

1. An internal combustion engine provided with double walls to form a water 65 jacket, the outer wall having an opening and

the inner wall having a projection within said opening, a cover plate for said opening, and a thimble in an opening in said projection and secured to the latter, having a spark-plug receiving opening, and means 70 co-operating with the outer end of said thimble to secure said cover plate.

2. An internal combustion engine having an opening through its head into the cylinder, and a thimble removably secured in said opening having an outwardly projecting flange on its outer end that overlaps the head adjacent said opening, said thimble having 75 an internal opening to receive a spark plug.

3. An internal combustion engine having 80 an opening through its head into the cylinder, and a thimble removably secured in said opening having an outwardly projecting flange on its outer end that overlaps the head adjacent said opening, said thimble having 85 an internal opening to receive a spark plug, the outer portion of said thimble opening enlarged and formed for engagement by a turning tool.

4. An internal combustion engine having 90 an opening through its head into the cylinder, and a thimble removably secured in said opening having an outwardly projecting flange on its outer end that overlaps the head adjacent said opening, said thimble having 95 an internal opening to receive a spark plug, said thimble flange being externally threaded, a cover plate having a hole through which said flange projects, and a nut on the flange.

5. A multi-cylinder internal combustion engine each cylinder having an opening through its head, a thimble secured in said opening and having at its outer end an externally threaded flange that overlaps the 105 head adjacent said opening, a one piece cover plate provided with holes through which the respective thimble flanges project, and a nut on each flange, outside said plate.

6. An internal combustion engine and 110 cylinder provided with double walls to form a water jacket, the outer wall having an opening and the inner wall having a centrally located spark plug receiving removable thimble entering an opening in said inner 115 wall and that reaches beyond the outer wall, a cover plate having a hole through which said thimble passes, the portion of said thimble throughout its length within the cover being of a size to pass through the cover hole, with the cover in place, and a clamping nut applied to the thimble outside the cover plate and engaging the latter.

7. An internal combustion engine and 125 cylinder provided with double walls to form a water jacket, the outer wall having an opening and the inner wall having a centrally located spark plug receiving removable thimble entering an opening in said inner wall and that reaches beyond the 130

outer wall, a cover plate having a hole through which said thimble passes, the portion of said thimble throughout its length within the cover being of a size to pass 5 through the cover hole, with the cover in place, and a clamping nut applied to the thimble outside the cover plate and engaging the latter, said cover plate having one or more holes for connecting the water 10 jacket with a source of supply of water.

8. An internal combustion engine and cylinder provided with double walls to form a water jacket, the outer wall having an opening and the inner wall having a cen-

trally located spark plug receiving removable thimble entering an opening in said inner wall and that reaches beyond the outer wall, a cover plate having a hole through which said thimble passes, the portion of said thimble throughout its length within 20 the cover being of a size to pass through the cover hole, with the cover in place, and a clamping nut applied to the thimble outside the cover plate and engaging the latter.

In testimony that I claim the foregoing I 25 have hereunto set my hand.

FRANK D. SHEPHERD.
